UNITED STATES PATENT OFFICE.

FRANK G. SLONEK, OF CHICAGO, ILLINOIS. ASSIGNOR TO R. M. HVID COMPANY, OF CHICAGO, ILLINOIS, A CORPORATION OF MICHIGAN.

FUEL-VALVE.

1,346,267.

Specification of Letters Patent. Patented July 13, 1920.

Application filed December 3, 1917. Serial No. 205,077.

To all whom it may concern:

Be it known that I, FRANK G. SLONEK, a subject of the Emperor of Austria-Hungary, and resident of Chicago, in the county of 5 Cook and State of Illinois, have invented certain new and useful Improvements in Fuel-Valves, of which the following is a specification

My invention relates to internal combustion engines and particularly to a novel fuel valve for use in connection therewith.

My invention is particularly applicable to engines of the Hvid type; that is, those in which ignition is effected by the heat of 15 compression and in which the liquid fuel charge is inhaled on the intake stroke

In all of the engines of the type in which liquid fuel is fed directly to the engine, the fuel valve must of necessity be of small dimensions; this for the reason that the amount of fuel necessary to be supplied for each power stroke is minute, and a small particle of foreign matter which may lodge 20 on the valve seat will prevent the closing of the valve and the escape of the high pressure of the cylinder into the fuel conduit, thus blowing out its contents. These difficulties follow the use of any valve which 25 lifts from its seat. An object in this invention is to provide a valve which never leaves its seat but rotates thereon, thus eliminating the difficulties heretofore referred to. This is readily accomplished in an engine of this 30 type wherein the fuel valve is of such relatively small size, the rotary movement of the valve to fully open and close the liquid intake port extending over only a few degrees.

The invention will be more readily understood by reference to the accompanying drawings, wherein,

Figure 1 is a vertical section through one end of an engine constructed in accordance with my invention;

Fig. 2 is a plan view thereof;

Fig. 3 is a bottom plan view of the fuel valve;

Fig. 4 is a similar view of a slight modification, and

Fig. 5 is a sectional view through the construction shown in Fig. 4.

In the drawings, the engine cylinder is indicated at 10, the usual piston 11, being provided therein. In the cylinder head I 55 provide a plug 10^a, having a firing or igni-

tion cup 10^b, at the lower end thereof, this being of the type commonly employed in engines of this type. The intake valve 12, is operated by a rocker 13, fulcrumed on the top of the cylinder and in this instance provided with an arm 14, which serves to actuate the fuel valve. In order to accomplish this, a link 15, is connected to the arm and is in turn connected to an arm 16, secured to the valve stem 17. A compression spring 18, surrounds the valve stem and tends to exert an upward pull thereon. The valve is in the form of a notched disk 19, the two notches being formed on diametric sides of the disk and when in one position the 60 notches register with the outlets or ports of oil and air passages 20, 21. When the valve is rotated a few degrees the oil and air ports are closed. Oil is supplied through a pipe 22, which may be controlled by a 65 valve 23.

In the construction shown in Fig. 4, the valve is in the form of a circular disk 24, having diametrically disposed apertures 25, 26, which are spaced in accordance with the 70 ports from the oil and air passages.

The advantage of the valve in the construction shown in Figs. 1 to 3 inclusive is that the sharp edge formed by the notched portion of the valve serves to scrape the 75 valve seat at each actuation and thus prevent the lodgment of any particles of foreign matter. Furthermore, it will be noted that this valve is never actuated against any pressure other than the pressure of the 80 spring which serves to seat the valve, the rotary actuation occurring only at the beginning and end of the intake stroke.

It will be apparent that the extent of opening of the valve or the length of time 85 during which it is opened or both may be controlled by a governor in any suitable manner. This is contemplated by me. It will furthermore be apparent that if desired a needle valve may be installed in the fuel 90 passage.

The valve may be modified in other particulars than that shown; that is, it may be provided with a tapered seat instead of a flat surface as is shown. These and other 105 modifications are considered within the spirit of my invention.

I claim:

1. In a hydrocarbon engine, the combination with a cylinder having an aperture in 110

its head, of a plug adapted to be mounted in said aperture, an ignition cup carried at the lower end of said plug, a rotary valve mounted within said cup, said valve being provided with a stem carried by the plug, a main valve rocker, and means connecting said rocker to said valve for rotating it, substantially as described.

2. In a hydrocarbon engine, the combination of a cylinder having a main valve and provided with an opening in its head, a plug seated in said opening, a fuel ignition cup carried at the lower end of said plug, said plug being provided with a fuel passage, a

disk valve mounted within the cup and adapted to close and open said fuel supply passage, spring means carried by the plug for resiliently holding said disk valve against its seat, a rocker for operating said main valve, and means connected with said rocker for rotating said disk valve, substantially as described.

Signed at Chicago, Illinois, this 1st day of December, 1917.

FRANK G. SLONEK.
